UNITED STATES PATENT OFFICE.

LEWIS O. CULVER, OF WEST PITTSTON, PENNSYLVANIA.

JAR CLOSURE.

Application filed April 16, 1924. Serial No. 706,837.

My invention relates to jar closures and is more especially adapted for use upon jars of the type commonly used for canning and preserving fruits or vegetables.

5 The objects of the invention are to provide simple and effective means for hermetically sealing such jars; to provide closing means which may be easily applied and removed without requiring any skill on the 10 part of the user, and to provide means which may be re-used indefinitely.

These objects, and other advantageous ends which will be described hereinafter, I attain in the following manner, reference 15 being had to the accompanying drawings in which—

Figure 1 is a side elevation partly fragmentary showing the top of a jar provided with one form of my invention,

20 Figure 2 is a view substantially at right angles to that of Figure 1;

Figure 3 a top plan view of Figure 2, and Figure 4 a section on 4—4 of Figure 1.

In the embodiment of my invention I provide a jar 2 of the usual form except that it 25 is equipped with oppositely disposed bosses 3 and 4 provided with vertical channels 5 preferably undercut at 6. I also provide a yoke 7, preferably of resilient metal, the 30 arms of which terminate in cross pieces 8 so that, when in use, each end of the yoke is in the form of an inverted T. Each of cross pieces 8 may be provided, at one end, with an angular lip 9. Midway of its length 35 the yoke is bored to receive a screw 10 provided with a wing head 11. I provide a cap 12 having in its upper surface a central depression 13 adapted to receive the end of screw 10. The under part of the cap is provided 40 with a downwardly extending annular tenon 14, preferably rectangular in cross section, and the top of the jar is provided with an annular channel 15 adapted to receive the tenon on the cap. The channel 45 is slightly larger in cross section than the tenon depending from the cap in order that it may receive a compressible gasket 16.

The attachment is simple, and inexpensive and the seal highly effective. It may be applied or removed almost instantaneously and re-used indefinitely. When removed the jar is free from any extraneous parts which interfere with cleansing.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In combination with a jar having an annular mortise in its upper surface and provided near its top with peripheral lugs having oppositely disposed vertical channels, and a cap having an annular depending tenon adapted to extend into the mortise in the jar, of a yoke having arms adapted to extend into the vertical channels, the arms having T-shaped ends adapted to extend under the lugs, and the arch of the yoke having a central bore, and a thumb screw extending through the bore and adapted to engage the cap.

2. In combination with a jar having an annular mortise in its upper surface and provided near its top with undercut peripheral lugs having oppositely disposed vertical channels, and a cap having an annular depending tenon adapted to extend into the mortise in the jar, of a yoke having arms adapted to extend into the vertical channels, the arms having T-shaped ends adapted to extend under the lugs, and the arch of the yoke having a central bore, and a thumb screw extending through the bore and adapted to engage the cap.

In testimony whereof I affix my signature.

LEWIS O. CULVER.
